(57) CLAIM

I claim the ornamental design for a massage adapter, as shown and described.

DESCRIPTION

FIG. 1 is a top, front, and right perspective view of a massage adapter showing my new design;

FIG. 2 is a front elevational view thereof, the rear, the left side, and the right side being mirror images;

FIG. 3 is a top plan view thereof;

FIG. 4 is a bottom plan view thereof;

FIG. 5 is a cross-sectional view taken along the line 5-5 in FIG. 2; and,

FIG. 6 is a perspective view showing the massage adapter in use.

The broken lines in the drawings illustrate portions of the massage adapter which form no part of the claimed design.
